CLAIM

The ornamental design for the copy holder set, as shown and described.

DESCRIPTION

FIG. 1 is a perspective view of an assembled copy holder set showing our new design, the two snaps of the right side of the top member being snapped onto the two snaps of the left side of the bottom member;

FIG. 2 is a perspective view thereof showing the top member separated from the bottom member;

FIG. 3 is a perspective view thereof showing the bottom member separated from the top member;

FIG. 4 is a top plan view of the top member shown in FIG. 2;

FIG. 5 is a bottom plan view of the top member thereof;

FIG. 6 is a right side elevational view of the top member thereof;

FIG. 7 is a left side elevational view of the top member thereof;

FIG. 8 is a top plan view of the bottom member shown in FIG. 3;

FIG. 9 is a bottom plan view of the bottom member thereof;

FIG. 10 is a left side elevational view of the bottom member thereof;

FIG. 11 is a right side elevational view of the bottom member thereof;

FIG. 12 is a front elevational view of the bottom member thereof;

FIG. 13 is a rear elevational view of the bottom member thereof;

FIG. 14 is a front elevational view of the top member thereof; and,

FIG. 15 is a rear elevational view of the top member thereof.
